(57) **CLAIM**

The ornamental design for a tow hook step combination, as shown and described.

DESCRIPTION

FIG. 1 is a perspective view of a tow hook step combination, in accordance with the present invention;

FIG. 2 is a right side elevation view of the tow hook step combination, in accordance with the present invention;

FIG. 3 is a top plan view of the tow hook step combination, in accordance with the present invention;

FIG. 4 is a left side elevation view of the tow hook step combination, in accordance with the present invention;

FIG. 5 is a front elevation view of the tow hook step combination, in accordance with the present invention; and, FIG. 6 is a bottom plan view of the tow hook step combination, in accordance with the present invention.

The broken lines depicting the axle, the circled letter B and the interior partitions on the bottom of the step plate illustrate portions of the article that form no part of the claimed design. The broken line structure illustrating the tow hook mount depicts environment that is not included in the claim.

1 Claim, 6 Drawing Sheets
